[57] ABSTRACT

A signature delivery and collating system which includes an inserter mechanism for inserting preprinted cards or sheets into pockets of a collator into which signatures are also fed from a continuous stream of overlapped signatures.

SIGNATURE COLLATING SYSTEM AND METHOD

This invention relates to a system for collating signatures for binding in a book or magazine or the like.

One known type of system for producing printed signatures utilizes a web fed press operating on a belt press principle together with a cutting, folding and collating apparatus which is synchronized with the press. This system is capable of producing, in a continuous operation, completely assembled books, minus their covers, ready for the binding operation. One such type of system is presently being marketed by the Cameron Machine Company, Dover, N.J.

One drawback to that known type of system has been the inability of the press to produce multiple color signatures. Moreover, being a continuous inline system, it has not been possible to introduce into the production process either insert cards or preprinted signatures that a publisher might wish to have included in a book, either in a random fashion or at known page numbers.

It is the primary object of this invention to provide in a continuous inline system in which signatures are delivered for collating in a continuous shingled stream, apparatus for feeding cards or preprinted signatures and combining them with signatures from the shingled stream.

More particularly, this invention is applicable to a system in which a conveyor transports a continuous stream of overlapped signatures from a printing press to a continuously movable collator having a series of pockets with the pockets being movable past the conveyor for receiving signatures therein and a cam separator for separating a predetermined number of signatures from the overlapped stream and displacing them into each pocket moving past the delivery conveyor. According to the principles of this invention, here is provided an insert or feed mechanism for selectively feeding inserts into pockets of the collator into which signatures from the overlapped stream are also fed. Thereafter, the combined signatures and inserts from a predetermined number of pockets are combined to form the completed book.

Referring now to the drawings in which but one form of the preferred embodiment is illustrated, the single Figure of the drawing is a schematic illustration, in side elevation, of the delivery conveyor, collator and insert mechanism.

There is disclosed in U.S. Pat. Nos. 3,502,321 and 3,558,125 apparatus of the general type with which this invention is concerned. As disclosed in those patents, a sheet delivery and collating mechanism is adapted to receive the signatures from a web-fed press which prints, folds and cuts the signatures in a continuous process. The signatures are fed from the press to a delivery conveyor which delivers the signatures in an overlapped or shingled condition to a collating mechanism. This collating mechanism comprises a continuously movable collator having a series of pockets which open toward the delivery conveyor and are movable past the conveyor for receiving signatures therein. A sheet separating and shifting member in the form of a cam separator is operable to separate the shingled signatures so that each pocket of the collator receives the correct number of signatures. The collator then delivers the signatures to delivery belts which transfer the collated signatures to a delivery station.

Referring now to the Figure of the drawing, essentially the same combination of elements as those dis-

closed in the above-referenced prior patents is illustrated. Thus, there is provided a delivery conveyor 10 which delivers signatures from the press (not shown) in an overlapped or shingled relationship to a collator, indicated at 14. Since the press prints the signatures in a repeat pattern, a certain length of the stream delivered by the conveyor 10 contains the signatures for each book. A sheet separating and shifting member in the form of a cam separator 16 is adapted to separate the signatures in the shingled stream and deliver the correct number of signatures to each pocket of the collator. The collator then delivers the separated signatures to a delivery belt 18 which delivers the signatures to a delivery station for subsequent binding.

As disclosed in the aforementioned patents, the collator 14 is provided with a series of pockets defined by spaced forks supported on an endless belt 20. However, in accordance with this invention, the belt 20 supports primary forks 22 with secondary or intermediate forks 24 positioned between the primary forks. Each of the forks 22, 24 is spaced from the next adjacent fork to define pockets 26 which open toward the delivery end of the conveyor 10 to receive signatures therein.

In association with the collator 14 there is provided an insert or feed mechanism schematically illustrated at 28. The insert mechanism may comprise a series of feeder belts which are adapted to feed, for example, insert cards or preprinted signatures. It is contemplated that the delivery conveyor 10, the collator 14, the cam separator 16, delivery belt 18 and the insert mechanism 28 will all be driven in synchronism by a suitable motor 32.

The cam separator 16 is adapted to function in the manner of the cam separator described in the aforementioned patents. However, unlike the cam separator in those patents in which only a single cam lobe is disclosed, the instant cam separator 16 is provided with a plurality of cam lobes 16a-d. Each cam lobe acts to depress the leading end of a group of signatures to guide them into the pocket 26 under a descending fork upon which the next following packet of signatures is to be deposited. By reasons of the design and position of the cam separator 16, each cam lobe is operative to separate a preselected number of signatures or sheets from the shingled stream and direct them into one pocket. For example, cam lobe 16a is operative to feed a preselected number of signatures into the pocket then adjacent the delivery end of the conveyor 10. As that pocket descends and the next fork moves into sheet receiving position, the cam separator will have rotated to a position where lobe 16b becomes operative to deliver the same preselected number of signatures or sheets to the next pocket. Thereafter, as the pockets continue to move downward, the cam lobe 16c and then cam lobe 16d become operative in the same manner, it being understood that each cam lobe operates on the shingled stream of signatures in the manner described in the aforementioned patent.

The operation of the illustrated mechanism will now be described. The following description will assume that three cards are to be inserted at spaced locations in each book produced by the press, it being understood, of course, that both the nature of the inserts, that is whether they are cards or preprinted signatures, as well as the number of the inserts may be varied.

The conveyor 10 delivers a shingled stream of sheets from the press. These sheets may be individual sheets

or signatures or packets of signatures, but in either case will be referred to as signatures. As the forks of the collator descend, two separate operations occur. The first is that the insert mechanism 28 is actuated to feed inserts C onto each of the secondary forks 24 between the primary forks 22. Thereafter, as a primary fork on which there is no insert moves past the sheet receiving position, one lobe of the cam separator 16 delivers the correct preselected number of signatures onto the primary fork. As each next succeeding secondary fork moves into a sheet receiving position, the lobes 16 b-d of the cam separator deliver the same number of signatures onto the top of the inserts resting on the secondary forks. The combination of the signatures on the primary fork and the inserts and signatures on each of the next three secondary forks make up one complete book, so that upon one complete revolution of the cam separator 16, the collator 14 will have moved downward by four forks. As cam lobe 16a again rotates to an operative position, the next succeeding primary fork 24 will have advanced to a sheet receiving position and the cycle will be repeated. In the meanwhile, the insert mechanism 28 will be periodically pulsed by a suitable mechanism 34, such as a timing cam or timing disc, so that inserts are deposited on each of the secondary forks as they descend by the insert mechanism.

As the forks carrying the signatures and inserts descend to the delivery belt 18, chain pins or lugs 36 coact with the collator 14 to remove the collated books. Each lug 36 removes the signatures from one primary fork and the signatures and inserts from the next three secondary forks so that each lug delivers a complete book to the delivery station.

Variations both in the described mechanism and its mode of operation may be made without departing from the principles of the invention. For example, although the insert mechanism 28 has been illustrated as delivering simultaneously inserts to each of three secondary forks, it will be appreciated that a single insert feeding mechanism could be used with the insert mechanism being pulsed each time a secondary fork passes by, rather than feeding three simultaneously. Also, the insert mechanism could be positioned beneath the conveyor 10 so that the insert cards are deposited on top

of the sheets resting on the secondary forks.

It will also be appreciated that the configuration of the cam separator may be varied. For example, instead of having four lobes, the cam separator may have a single cam lobe much in the manner of the cam separator disclosed in the aforementioned patents. However, with such a configuration, the cam separator would be rotated four times faster so that the cam separator would make one complete revolution as the collator 14 descends by a distance equal to the space between two adjacent forks.

Other variations and modifications will be apparent to those skilled in the art so that although the invention has been described with reference to a specific embodiment, neither the illustrated embodiment nor the terminology employed in describing it is intended to be limiting; rather, it is intended to be limited only by the scope of the appended claims.

Having thus described the invention, what is claimed is:

1. A method of collating at least one insert and signatures to produce assemblages of sheet material such as magazines, books or the like, said method comprising the steps of,

feeding the signatures in a continuous shingled stream with the signatures arranged in a repeat pattern such that only a portion of the signatures in the stream are to be used for each book,

separating the portion of the stream for each book into a plurality of separate groups of signatures by feeding groups of signatures into continuously movable pockets,

associating inserts with at least some of the groups of signatures by feeding inserts into selected ones of said continuously movable pockets, and

combining the separate groups of signatures and at least one insert by simultaneously removing the signatures and at least one insert from a plurality of the movable pockets.

2. The method of claim 1 wherein said step of associating inserts further comprises feeding the inserts into said pockets before the signatures are fed into said pockets.
